UNITED STATES PATENT OFFICE.

DONALD G. LITTLE, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

COMBINATION OF INDUCTANCES FOR WIRELESS.

Application filed June 3, 1921. Serial No. 474,724.

To all whom it may concern:

Be it known that I, DONALD G. LITTLE, a citizen of the United States, and a resident of Edgewood Park, in the county of 5 Allegheny and State of Pennsylvania, have invented a new and useful Improvement in Combinations of Inductances for Wireless, of which the following is a specification.

My invention relates to the coupling of 10 vacuum tubes to antenna circuits and, more particularly, it relates to the coupling of vacuum tubes of the feed-back type to antenna circuits in either radio telephony or radio telegraphy.

15 One object of my invention is to allow the tuning of the antenna circuit to be varied without changing the amount of feed-back voltage induced in the grid circuit by the current in the plate circuit.

20 A further object of my invention is to devise a system for the accomplishment of the above outlined object that shall have but few elements and be simple in construction and manipulation.

25 In regenerative continuous-wave systems, it is essential that the feed-back voltage induced in the grid circuit by the current in the plate circuit shall remain constant, within narrow limits, regardless of the wavelength to which the system is tuned. Heretofore, it has been impossible to adjust the tuning of such systems with the assurance that the feed-back adjustment will remain correct, and it has been necessary to go 30 through a tedious process of testing and experimentation in order to find the value of inductances necessary to give both the correct wave-length and the correct feed-back adjustment.

40 In my system, for receiving, I provide an antenna circuit comprising an antenna inductance device formed of two series-connected coils, the relative position of which is adjustable. This antenna inductance device operates as a feed-back coil and is also conductively connected in the grid circuit of a three-electrode vacuum tube of the feed-back type. An inductance coil in the plate circuit of the tube is inductively coupled to 45 the antenna inductance device, and the value of the antenna inductance device may be varied without altering the voltage of the feed-back connection.

In the sending apparatus, an antenna inductance device formed of the two adjustable coils is located within the plate circuit of the tube, and the length of wave transmitted may be varied without varying the voltage induced in a feed-back coil inductively coupled to the antenna inductance 50 device.

In the drawings:

Figure 1 is a diagrammatic view of circuits and apparatus utilizing the principles of my invention, in which a three-electrode 55 vacuum tube operates as a receiver.

Fig. 2 is a similar view illustrating a sending system employing a three-electrode vacuum tube having circuits coupled in accordance with my invention.

Fig. 3 is a similar view illustrating a modification.

In Fig. 1 is shown an antenna circuit comprising an antenna 1, a variable condenser 2 and a variometer 3 formed by two coils 4 and 5 connected in series and adjustable in relative position. In practice, the inductance coil 5 is wound on a small form and is mounted to rotate inside of the coil 4. Thus, the inductance of the variometer 3 may be changed to vary the wave length of the antenna circuit. From the variometer 3 the antenna circuit is connected to ground.

Inductively coupled to the variometer 3 is a coil 6. In practice, the coils 6 and 4 are preferably wound on the same form and have, therefore, mutual inductance. The coil 6 has, likewise, mutual inductance with the combination 4—5, which changes for 80 various positions of the coil 5. With proper design of the coils 4, 5 and 6, the voltage induced in coils 4 and 5 by coil 6 may be maintained substantially constant for all 85 adjustments of the combination 4—5.

A three-electrode receiving bulb 7, having a grid element 8, a plate element 9 and a filament element 11, has its grid circuit conductively connected to the antenna circuit, the leads being taken from opposite sides 100 of the variometer 3. To provide suitable current to heat the filament 11, I have shown an "A" battery 12. The induction coil 6 is connected in the plate circuit of the tube which likewise comprises a plate battery 13 and a telephone receiver 14. To

provide a proper by-pass for radio-frequency currents, I have shown a by-pass condenser 15 which shunts the telephone receiver 14 and the plate battery 13.

- 5 By suitably shaping and proportioning the tuning reactor 2 and the coil 5, having due regard to the coils 4 and 6 and the particular characteristics of induction and capacity of the aerial construction employed, the combined tuning variometer and feed-back coil 4, 5, 6 may be devised in accordance with the design hereinbefore described, whereby the voltage induced in the variometer 3 by the current flowing in the coil 6 may be held 10 constant within sufficiently close limits to permit satisfactory regenerative operation for all adjustments of the variometer 3.

If desired, a common mechanical connection 16 may be added in order to cause 20 the tuning condenser 2 to vary at the same time as the variometer 3, although my invention is not limited to such construction. In this manner, the receiving set illustrated 25 in Fig. 1 may be tuned without disturbing the regenerative operation thereof.

Referring to Fig. 2, I have shown a sending system employing a three-electrode vacuum tube of the feed-back type coupled in accordance with the principles of my invention. The antenna circuit comprises an antenna 1 and a variometer 17 corresponding to the variometer 3 of the antenna circuit described in connection with Fig. 1. The variometer 17 is formed of two coils 18 and 19 connected in series. The coil 19 may be mounted to rotate within the coil 18 whereby the relative positions of the coils 18 and 19 may be changed in order to vary the effective inductance of the variometer 40. 17. The antenna circuit is connected, through a variable condenser 21, to ground.

In inductive relation to the variable inductance device 17 is a coil 22 which is preferably wound on the same form as the coil 18. There is thus mutual inductance between the coils 18 and 22, as there is likewise between the coil 22 and the combination 18—19. The mutual inductance between the coil 22 and the coils 18 and 19 varies for various positions of the coil 19 within the coil 18. The design is such that the voltage induced in the coil 22 by the variometer 17 will be substantially constant for all adjustments of the variometer 17.

55 A three-electrode vacuum tube 23, acting as an oscillator and having a plate element 24, a grid element 25 and a filament element 26, has its plate circuit coupled conductively to the antenna circuit, the leads being taken 60 from the antenna end of the variometer 17 and the ground connection. Shunted around the variable condenser 21 of the antenna circuit is a direct-current generator 27 which supplies direct current to the plate circuit of the tube. In the grid circuit

is located the inductance coil 22 previously described. The filament 26 is heated by means of a suitable filament battery 28.

The tube 23 operates as a generator of continuous oscillations by reason of the feed-back coupling between the grid and plate circuits. The feed-back voltage induced in the coil 22 of the grid circuit by the plate current flowing in the variometer 17 is substantially constant for all adjustments of the variometer 17. The output of the tube 23 tends to remain constant since the potential induced on the grid 25 remains constant.

In Fig. 3, I have shown a more general solution of the problem, as applied to a receiving circuit. The system shown in Fig. 3 is the same as that shown in Fig. 1 except that the tuning condenser 2 is omitted and the coil 6, instead of being rigidly mounted with respect to the coil 4, is wound on a separate form 30 which is pivoted at one end, as at 31. The other end of the form 30 is provided with a pin 32 which rides in the slot 33 of any suitable cam device 34, the shape of which may be determined experimentally. The cam is pivoted as at 35 and is mechanically connected to the variometer 3, as indicated schematically by the connecting means 36. In this manner, the relative positions of the coil 6 and the variometer 3 may be adjusted simultaneously with the adjustment of the variometer in order to facilitate the achievement of the substantially constant feed-back voltage for which my system is designed.

While I have shown several forms of my invention in the appended drawings, I do not wish to be restricted thereto but I desire that only such restrictions shall be placed upon my invention as are set forth in the appended claims.

I claim as my invention:

1. In a radio device, a regeneratively connected vacuum tube, including a reactor in the grid circuit, a reactor in the plate circuit coupled thereto, means for adjusting each of the said reactors independently, and means mechanically associated with one of said adjusting means for adjusting the relative position of said reactors when the associated adjusting means is actuated, to thereby vary the coupling between said reactors when the reactance of one of them is varied.

2. In a radio device, a regeneratively connected vacuum tube, including a reactor in the grid circuit, a reactor in the plate circuit coupled thereto, means for adjusting each of the said reactors independently, and means mechanically associated with one of said adjusting means and including a cam for adjusting the relative position of said reactors when the associated adjusting means is actuated to thereby vary the coupling between said reactors when the reactance of

one of them is varied, said cam being so shaped that the coupling corresponding to each value of said reactance is optimum.

3. In a radio-receiving set an antenna circuit including a variometer, a regenerative vacuum-tube device, said variometer being in the grid circuit of said vacuum-tube device, an adjustable inductor in the plate circuit of said vacuum-tube device coupled to said variometer, said coupling constituting the feed-back of said regenerative vac-

uum-tube device, means for varying the position of said indicator relative to said variometer, to thereby vary the feed-back coupling and means mechanically actuated by 15 said inductor for controlling said position-varying means.

In testimony whereof, I have hereunto subscribed my name this 31st day of May, 1921.

DONALD G. LITTLE.
